HAROLD A. WHEELER, OF JACKSON HEIGHTS, NEW YORK, ASSIGNOR TO HAZELTINE CORPORATION

RADIOFREQUENCY TRANSFORMER

Original application filed June 20, 1929, Serial No. 372,275. Divided and this application filed May 28, 1930.
Serial No. 456,474.

This invention relates to high-frequency thermionic amplifiers and more particularly to turnable amplifiers of this type wherein by the utilization of suitable coupling networks containing capacitive and inductive impedance elements associated with the input sections of the successive amplifier stages, the amplification may be caused to vary in a preselected manner as the tuning is varied over a desired frequency range.

This application is a division of my copending application, Serial No. 372,275, filed June 20, 1929.

An object of the invention is to embody in an amplifier having the above characteristics, neutralizing means for minimizing any feedback of energy from the output to the input sections of the individual amplifier stages during operation, which energy transfer usually occurs as a result of the interelectrode capacities of the thermionic tubes and tends to set up sustained oscillations with resultant signal distortion, squeals and whistles.

A second object of the invention is to provide an amplifier of the type specified adapted for use in radio receiving systems and characterized by the feature that the effective output impedance of the successive amplifier stages is predominantly capacitive over the range of operating frequencies, whereby the effective antenna capacity may be quite simply adjusted to approximate the capacitive impedances of the successive amplifier stages thereby permitting the use of a coupling network between the antenna and first amplifier stage which is identical both in construction and tuning characteristics with the networks associated with the succeeding stages.

A further object of the invention is to furnish specific design data for a high-frequency transformer structure the use of which as a part of the coupling networks will result in a high and substantially uniform de-

gree of amplification over a desired radio-frequency range.

Other objects will become apparent from the subsequent detailed description.

It is a well known fact that by interposing between successive amplifier tubes a coupling network having a primary transformer winding across the output terminals of the first tube and a tuned secondary winding across the terminals of the succeeding tube, an amplifier is obtained wherein the overall amplification and also the impedance across the output of the first tube increases as the tuned frequency is increased. The increased amplification with frequency is undesirable since it prevents the amplifier from being uniformly sensitive and free from oscillations over a wide range of frequencies. The increase with frequency of the primary impedance is the cause of the corresponding increase of amplification and of feedback currents from plate to grid of the tube.

In order to overcome the disadvantages of the generally known standard type of coupling system, C. E. Trube in his application for United States Letters Patent, Serial No. 120,045, filed July 2, 1926, and Patent No. 1,763,380, issued June 30, 1930, has disclosed improved types of coupling systems, by the proper design of which the amplification of a system may be caused to vary in a preselected manner as the tuning frequency is adjusted over a desired range. These coupling systems are in general characterized by the additional feature that the total primary impedance connected thereby across the output terminals of a tube may be substantially constant or even decreasing with increased frequency, thereby minimizing the tendency for the setting up of sustained oscillations at the higher frequencies due to the regenerative feedback action of the tubes.

To accomplish the above results, the mentioned Trube coupling systems employ a coupling network one portion of which has a

capacitive reactance over a desired high-frequency range and another portion an inductive reactance over the same range. The impedance, and hence the voltage, across the capacitive element, of course, decreases with increase in frequency; while for the inductive element the same factors increase with frequency. By suitably proportioning the capacitive and inductive elements relatively and suitably coupling the same with the input terminals of the succeeding tube, it is apparent that the resultant effect on the tube input can be caused to vary in a preselected manner with frequency over a desired range. Likewise, if the capacitive and inductive elements be suitably connected across the output terminals of the preceding tube as, for example, by connecting them in series, then the impedance across the tube output can likewise be caused to vary in a desired manner with frequency, for as the impedance of one element increases, that of the other element decreases and any desired resultant effect may be obtained.

Despite the improvements introduced by the Trube coupling systems, the amplification obtainable is still limited by the feedback action of the tubes at the higher frequencies, because of the fact that the coupling between grid and plate circuits due to the interelectrode tube capacity increases with increase in frequency. The present invention, therefore, embodies in an amplifier utilizing the Trube coupling networks, suitable neutralizing means for minimizing transfer of energy from the output to the input of the successive tubes. With such an arrangement all the advantages of the Trube system are available and in addition a much higher degree of amplification over a desired frequency range is attainable.

When utilizing high-frequency amplifiers in radio receiving systems, it is desirable that the antenna system have the same impedance characteristics over the operating frequency range as the output impedance of the successive amplifier stages, since such an arrangement permits the same type of coupling network to be efficiently utilized between the antenna and the first amplifier stage as is used to interconnect the successive stages.

For effective operation, the coupling networks must be designed to work efficiently between the impedances which they interconnect. Thus if, as is generally the case, the antenna impedance is quite different from the output impedance of the successive amplifier stages, optimum design would call for a type of coupling network between the antenna and the first amplifier tube different from that utilized for interstage coupling.

Such a non-uniform arrangement is, of course, undesirable from a manufacturing standpoint since cheaper set construction could be obtained with the same type of cou-

pling networks utilized throughout the receiving set. Also from an operating standpoint, the above described arrangement is undesirable since the first coupling network would tune at a different adjusting position from the others, which would prohibit the use of unitary control means including gang condensers and the like for tuning purposes.

The present invention provides a neutralized high-frequency amplifier wherein the output impedances of the successive amplifier stages are capacitive over the operating frequency range, due to the use of a relatively large neutralizing condenser connected to each plate. Thus, by suitably proportioning the antenna structure or associating a fixed capacity of proper magnitude with the antenna circuit, the resultant antenna capacity can be made to approximate the neutralizing capacities of the amplifier stages. As a result, the same type of coupling network may be utilized for coupling the antenna and first tube as is utilized interstage and, furthermore, such networks will be identically tunable, thereby embodying in the amplifier the advantages of unit-controlled tuning pointed out above.

Referring now to the drawings:

Fig. 1 shows a circuit diagram of a complete radio receiving system embodying a unit-controlled, tuned high-frequency amplifier constructed in accordance with the present invention.

Figs. 2 and 3 show modified circuit arrangements which are approximately equivalent to the circuit of Fig. 1.

Figs. 4 and 5 disclose the structural details of a special three-winding high-frequency transformer which is suitable for use in the coupling networks of Figs. 1, 2 and 3.

Referring now to Fig. 1, the receiving system comprises thermionic tubes 1 and 2 operating as amplifiers and tube 3 operating as a detector. Each tube has a grid G, a filament or cathode K constituting an input section commonly referred to as the grid circuit, and a plate P cooperating with the filament or cathode K to form an output section commonly termed the plate circuit of the tube. The batteries 4 supply the necessary negative bias on the grids of the amplifier tubes, while the batteries 5 supply the necessary direct-current voltages for the plate circuits of the successive tubes. Batteries 14 furnish the necessary energy for heating the filaments or cathodes, K.

Associated with the input to each tube is a coupling network comprising capacities C and C₃ together with a three-winding transformer T having a single secondary and two primary windings. The secondary winding L₁ shunted by the variable capacity C constitutes a tunable resonant circuit connected between grid and filament of the succeeding tube. The primary circuit connected between

plate and filament of the preceding tube, or to the antenna system terminals 11, comprises the winding L_3 shunted by the fixed capacity C_3 together with the winding L_2 connected in series with L_3 but in the reverse direction. 5 A neutralizing capacity C_2 which serves to neutralize feedback of energy from the plate circuit to the grid circuit of the tube is in each case, in Fig. 1, connected from the plate to a point between the primary windings 10 L_1 and L_2 .

The capacity C is adapted to tune the secondary circuit over a desired frequency range, say from 550 to 1500 kilocycles, under present broadcasting conditions in the 15 United States. The capacity C_3 is selected to tune the parallel circuit L_3C_3 to a frequency somewhat lower, usually but slightly lower, than the lowest frequency of tuning. 20 Under the above assumption L_3C_3 would be resonant at about 400 kilocycles. Over the operating range of frequencies the circuit L_3C_3 thus has a capacitive reactance; which means that the impedance decreases continuously as the frequency increases. On the other hand, winding L_2 being substantially 25 purely inductive, its impedance increases proportionally with increased frequency. Due to the small inductance and small distributed capacity of coil L_2 its resonant frequency is so much higher than the upper limit of the tuning range of the coupling system that L_2 may be considered by itself as untuned or effectively non-resonant. The 30 coefficient of coupling between L_1 and L_2 is, however, such that L_2 is tuned by L_1-C . 35

Since the oppositely varying impedances are serially connected between plate and filament of the tube, the resultant impedance 40 may be adjusted to vary as desired with frequency, preferably decreasing with increase in frequency.

Coming now to the effect produced by the primary on the secondary circuit L_1C , since 45 the coupling between L_1 and L_2 is constant over the frequency range, the voltage induced in L_1 by L_2 increases with frequency due to the increasing impedance and hence proportionally greater voltage drop across 50 L_2 . On the other hand, the effect produced in L_1 by L_3 decreases with frequency, since as the frequency goes up an increasing percentage of the total primary current flows through the capacity C_3 . In effect, the capacity C_3 shunting L_3 provides a means for 55 automatically reducing the coupling between L_3 and L_1 as the frequency increases.

Thus there are two factors operating on the secondary circuit, one of which increases 60 and the other of which decreases as the frequency is varied by tuning. By suitably proportioning these factors relatively, the resultant effect produced in the secondary circuit can be caused to vary in a preselected manner with frequency. In general, it is desir-

able to have a design such that the overall amplification of the system remains substantially constant over the operating frequency range. Due to the presence of capacity C_3 , the current in winding L_2 is in 70 phase opposition to that in L_3 over the operating frequency range. Hence it is necessary to connect windings L_2 and L_3 series opposed in order to obtain additive effects in winding L_1 . 75

The winding L_2 in addition to its function as forming part of the primary circuit of the coupling network in the manner explained above, also cooperates with the capacity C_2 to neutralize the coupling effect occurring 80 between the plate circuit and grid circuit of a tube as a result of the interelectrode capacity C_1 . Regenerative feedback occurring between the plate and grid circuits of a thermionic tube, as is well known, is prevented when the circuit arrangements are such that a voltage active in the plate circuit of the tube can produce no effect in the grid circuit thereof. This condition is commonly referred to as neutralization. Referring to 85 Fig. 1, if the high-potential terminal of winding L_2 be of opposite alternating-current polarity to that of winding L_1 , no regenerative feedback will occur when the following relation obtains: 90

$$\frac{C_2}{C_1} = \frac{L_1}{M_{1-2}} \quad (1)$$

where M_{1-2} is the mutual inductance between windings L_1 and L_2 . Consider a voltage across the primary circuit associated with the output of tube 2. Such a voltage will cause two capacity currents to flow to ground. The first capacity current flows from plate to grid of tube 2 through the interelectrode coupling capacity C_1 and thence through winding L_1 to ground at 9. The second capacity current will flow from plate P through the neutralizing condenser C_2 , through the winding L_2 , and in series through 100 batteries 5 and 4 associated with the tube 1 to ground at 13. If the elements are so proportioned that Equation (1) above is satisfied, then the current thus flowing through winding L_2 will induce a voltage in winding 110 L_1 , which is equal and opposite to the self-induced voltage in winding L_1 due to the current flowing therein. The resultant induced voltage in winding L_1 will therefore be 115 zero, and hence no voltage will be impressed between grid and filament of the tube. 120

In order that the neutralization obtained in this manner be effective at all frequencies, it is necessary that the coupling between 125 windings L_1 and L_2 be as close as practicable. The coupling coefficient between these two windings in this case should be about 50% or greater if possible. If the coupling coefficient is too low, the capacity C_2 required 130

for exact neutralization will vary considerably with frequency.

In order that the amplifier have a uniform gain over the operating frequency range, it is required that the inductance L_3 be relatively large, and L_2 be relatively small as compared to L_1 . In practice, L_2 amounts to only a few turns of wire. This means, of course, that the mutual inductance between windings L_1 and L_2 will be quite small as compared to the self-inductance of winding L_1 , and if reference be had for a moment to Equation (1) above, it will be seen that under such conditions the neutralizing capacity C_2 required will be very large as compared to the plate-to-grid interelectrode capacity C_1 . In an actual design neutralizing capacities of the order of 130 mmf. have been used.

Now referring for a moment to tube 2 of Fig. 1, it will be noted that the capacity C_2 is connected from the plate P through the winding L_2 to ground, and is thus effectively in parallel with the output circuit of the tube. Owing to the large value of capacity C_2 , its impedance over the operating frequency range is relatively small as compared to the filament-to-plate resistance of the tube and also as compared to the impedances introduced between plate and filament thereof due to the interelectrode tube capacities occurring between the plate and grid, and plate and filament electrodes, all of which impedances are effectively in parallel with the impedance of the neutralizing capacity C_2 . In general, the impedance of C_2 over the operating frequency range is about 1000 ohms, as compared to a filament-plate resistance of about 10,000 ohms, a filament-plate interelectrode capacity negligibly small, and a grid-to-plate interelectrode capacity C_1 of 3 to 10 mmf.

The apparent output impedance of the tube is, therefore, approximately that of the capacity C_2 throughout the operating frequency range. More accurately, this apparent output impedance of the tube is represented by the total capacity, $C_2 + C_1$ plus that introduced by leads and wiring.

The usual capacity of an antenna used with ordinary commercial receiving sets is of the order of 200 mmf. Referring to Fig. 1, by connecting in a suitable capacity 8 of say 250 mmf. in series with such an antenna 7 having a capacity of about 200 mmf., the resultant capacity of antenna and wiring is of the order of 130 mmf., so that the antenna circuit will have a capacitive impedance over the operating frequency range which simulates the apparent output impedances of the successive tubes as approximately determined by the capacity C_2 . The advantage of such a design, of course, lies in the fact that the same type of coupling network may be utilized between the antenna circuit and the first tube 1 as is utilized for interconnecting the successive

tubes, with the resultant advantages in construction and operation pointed out above.

The fixed capacity 8 is optional, and may be omitted if the antenna used in a specific case has a low capacity value, say of the order of 130 mmf. In practice, it has been found sufficient to provide a single capacity 8 of approximately 250 mmf. If the antenna impedance happens to be high, the capacity 8 is connected in series therewith, and if it happens to be low, the capacity 8 is short-circuited.

It will become apparent from the discussion given above that the circuit arrangement disclosed in Fig. 1 is very efficient and economical in that the winding L_2 serves a double purpose, i. e., as a portion of the primary circuit and also as a portion of the neutralizing circuit. Likewise, the capacity C_2 serves a double purpose, i. e., as a portion of the neutralizing circuit and as a means for furnishing a capacitive output reactance, thereby permitting identically constructed and identically tunable coupling networks to be utilized throughout the receiver.

It has been found that the best results are obtained when the coupling between windings L_1 and L_3 is not too loose. The coupling under such conditions might be termed moderate and will be so referred to in the appended claims. A moderate coupling, in this case, is one wherein the coupling coefficient has a value lying between the limits of about 10% and 50%. On the other hand, the coupling between windings L_2 and L_3 should be loose, i. e., having a value less than about 30 percent, while still fulfilling other requirements. In actual coil construction, this figure can usually be met due to the fact that the coupling between windings L_2 and L_3 can be as loose as is consistent with the necessary degree of coupling between windings L_1 and L_3 and between windings L_1 and L_2 . The ideal condition is attained when the coupling coefficient between windings L_2 and L_3 equals the product of the coupling coefficients between windings L_1 and L_2 and between windings L_1 and L_3 , i. e., when

$$K_{2-3} = K_{1-2} \cdot K_{1-3} \quad (2)$$

where K represents the coupling coefficient, and the subscripts denote the windings between which the coefficient is given. This equation is approximately satisfied by the design shown in Figs. 4 and 5, as will be seen from the description below.

Fig. 2 shows an alternative circuit arrangement which is a modification of that shown in Fig. 1, and may therefore be substituted for the arrangement of Fig. 1 either as an antenna coupling system or as an inter-tube coupling system. In Fig. 2, the primary circuit is both inductively and conductively coupled to the secondary circuit. The capacity C_3 is connected from the plate of the

preceding tube to an intermediate tapping point on L_1 , while the winding L_3 is connected in a reversed sense between plate and filament of tube 1 as compared to its mode of connection in Fig. 1. The tapped portion of winding L_1 in Fig. 2 takes the place of winding L_2 in the primary circuit of Fig. 1, and in Fig. 2 the winding L_2 serves as a neutralizing winding only. The circuit of Fig. 2 is electrically equivalent to that of Fig. 1. The only difference consists in combining the separate primary and secondary windings L_2 and L_1 of Fig. 1 into the auto-transformer arrangement of Fig. 2. At the lower frequencies, the capacity C_3 is, in Fig. 2, effectively in shunt with the winding L_3 because the reactance of the tapped portion of L_1 is negligibly small at such frequencies. The circuit L_3C_3 is resonant at a frequency slightly below the minimum frequency of the tuning range of the condenser C , as was the case for Fig. 1.

Fig. 3 shows a circuit arrangement similar to that of Fig. 2 with the exception that the condenser C_3 is connected from the plate of the preceding tube to the upper terminal winding L_1 . By suitably selecting the value of C_3 this circuit may be made electrically equivalent to that of Figs. 1 and 2. In this case the circuit $L_3C_3L_1$ is tuned to a frequency slightly below the tuning range covered by the condenser C . In Figs. 2 and 3, the capacity C_3 is decreased and the inductance L_3 is increased when the tap on coil L_1 is moved upward to include more turns.

The circuit arrangement of Figures 1, 2 and 3 are claimed in my above-mentioned application, Serial No. 372,275 of which the present application is a division.

The structural details and design data of a transformer which has been successfully used in the circuit arrangement of Fig. 1 will be given with reference to Figs. 4 and 5. Referring more particularly to Fig. 5, the windings L_3 , L_1 and L_2 are of cylindrical form, each comprising a single layer of wire uniformly wound about the tubular sections h , i and j , respectively, of insulating material, preferably bakelite. The tubular sections are of successively decreasing diameter as shown, and are positioned coaxially one within another in fixed spacial relationship by means of the bolts n and spacing members m . The secondary winding L_2 being of intermediate diameter is positioned between the primaries with the larger primary L_3 surrounding the same and the small primary L_2 on the inside.

The diameter of section j is only slightly less than that of i in order to provide the highest practicable coefficient of magnetic coupling between the windings L_1 and L_2 . The diameter of section h is considerably greater than that of section i in order to provide moderate coupling between the large

primary L_3 and the secondary L_1 . By positioning the primary windings L_2 and L_3 on opposite sides of the secondary L_1 , a small degree of magnetic coupling is obtainable between the two primaries, while at the same time providing the necessary coupling between the primaries and the secondary. The loose coupling between L_2 and L_3 is further enhanced by positioning L_2 toward one end of L_3 .

There are several advantages in placing the large primary L_3 on the outside of windings L_2 and L_1 . It will be recalled that the large primary has connected in shunt therewith a capacity of relatively low reactance over the tuning frequency range. As a result, the winding L_3 acts in effect as an electrostatic and electromagnetic shield substantially surrounding windings L_1 and L_2 , with resultant minimization of the external fields set up by the currents in these windings and consequent improved operation of the receiving system through reduction of undesired couplings.

The shielding action of winding L_3 does not increase the effective resistance of winding L_1 over its value with L_3 on open circuit, for the reason that with L_3 on open circuit, the magnetic flux distribution due to a current in winding L_1 is such as to crowd the current in the turns of wire toward the axis of the coil, causing the same to flow through only a portion of the conducting cross-sectional area, thereby increasing the total effective resistance in the path of the current flow. With winding L_3 short-circuited by capacity C_3 , however, there occurs a redistribution of flux caused by a current flowing in winding L_1 , since owing to the presence of the shield the flux external to the coil L_1 tends to flow between the coils L_1 and L_3 . This flux redistribution of L_1 causes the current to be more uniformly distributed over the cross-sectional area of the turns of wire, with resultant decrease in total coil resistance. On the other hand, the magnetic field set up by the current in L_1 causes a dissipation of energy in L_3 which appears as an added resistance in L_1 . The net effect, therefore, is that the effective resistance of L_1 is about the same whether L_3 is on open or short circuit, or entirely removed. This same advantage is obtained also when L_3 has the form of a multi-layer coil surrounding L_2 . As contrasted with the above arrangement, if L_3 were of smaller diameter and thus placed inside of L_1 , the total resistance of winding L_1 would be increased because both of the above described effects would increase the apparent resistance of L_1 , i. e., the current in L_1 would be crowded in the portion of the conducting cross-section toward the axis, and in addition the flux set up by the current in L_1 would cause a dissipation of energy in L_3 .

In an actual embodiment of the present in-

vention which operated in a very satisfactory manner, the following dimensions were utilized in the construction of coils of the type shown in Figs. 4 and 5. The dimensions are indicated by the letters in Fig. 5 and were as follows:

10

$$\begin{aligned}a &= 1 \text{ inch} \\b &= 2.42 \text{ inches} \\c &= .688 \text{ inch} \\d &= 1.25 \text{ inches} \\e &= 2.5 \text{ inches} \\f &= 1.5 \text{ inches} \\g &= 1.25 \text{ inches}\end{aligned}$$

cylinders h , i and j were each of insulating material having a wall thickness of $1/16$ inch.

Winding L_3 comprised 200 turns of #30 B & S gauge enameled copper wire, uniformly wound 80 turns per inch; winding L_1 comprised 126 turns of #26 B & S enameled wire, wound 52 turns per inch; while winding L_2 comprised 11 turns of #26 B & S enameled wire, wound 16 turns per inch.

Measurements made at 1,000 cycles per second to determine the electrical constants of the various windings gave the following results. The self-inductances of the windings measured in microhenries were:

30

$$\begin{aligned}L_3 &= 1710 \text{ microhenries} \\L_2 &= 5.4 \text{ microhenries} \\L_1 &= 294 \text{ microhenries}\end{aligned}$$

35

$$\begin{aligned}M_{1-3} &= 375 \text{ microhenries} \\M_{2-3} &= 25.2 \text{ microhenries} \\M_{1-2} &= 18.5 \text{ microhenries}\end{aligned}$$

40

The mutual inductances were as follows: where M is the mutual inductance, and the subscripts represent the windings between which the mutual inductance is measured as, for example, M_{1-3} refers to the mutual inductance between windings L_1 and L_3 . The coefficients of magnetic coupling between the windings, in percent, were as follows:

45

$$\begin{aligned}K_{1-3} &= 53 \text{ percent} \\K_{2-3} &= 26 \text{ percent} \\K_{1-2} &= 46 \text{ percent}\end{aligned}$$

50

The value of K_{1-3} is approximately the upper limit of "moderate coupling", as previously defined; and the value of K_{1-2} is approximately the lower limit for the coupling between L_1 and L_2 , as described above. The product of K_{1-3} and K_{1-2} is substantially equal to K_{2-3} .

55

In a radio receiving system of the type shown in Fig. 1 utilizing type UX-201-A tubes, and coils of the type shown in Fig. 4 having the constants given above, the following values were used for the remaining electrical elements. The capacity C_3 was of 250 mmf.; for the neutralizing capacity, C_2 a value of 130 mmf was found satisfactory; for use in the antenna circuit the fixed capac-

itry 8 had a value of 250 mmf.; and the variable condenser C was continuously adjustable between the limits of 30 and 400 mmf.

I claim:

1. A transformer comprising two primary windings and a secondary winding so positioned relatively that the product of the coupling coefficients between one primary and the secondary and between the other primary and the secondary equals the coupling coefficient between the two primary windings.

2. The combination of a transformer comprising a distributed primary winding surrounding an inner secondary winding, and a relatively low impedance connected between the terminals of said distributed primary winding whereby said primary winding acts substantially as an electrical shield surrounding said secondary winding.

3. In combination, a transformer comprising one or more windings positioned within an outer distributed winding in fixed spacial relationship, and a relatively low impedance connected between the terminals of said outer winding for rendering the same effective as an electrical shield substantially surrounding said inner windings.

4. A high-frequency transformer comprising three tubular sections of insulating material of successively decreasing diameters, means positioning said sections coaxially one within another in fixed spacial relationship, and windings individual to said tubular sections, each said winding comprising a single layer uniformly wound about the corresponding tubular section and extending over a certain portion thereof, the intermediate and inner windings being situated substantially within the confines of said outer winding, and the diameters of said tubular sections being proportioned to provide a desired degree of magnetic coupling between said outer and intermediate windings, and between said intermediate and inner windings while at the same time providing a relatively loose magnetic coupling between said outer and inner windings due to the positioning thereof on opposite sides of said intermediate winding.

5. A high-frequency transformer comprising three helical windings positioned one within another, the innermost winding comprising a small number of turns and the intermediate and outermost windings comprising a relatively large number of turns, the spacing between said intermediate and innermost windings being relatively small as compared with the spacing between said intermediate and outermost windings whereby the coefficient of coupling between said intermediate and innermost windings is substantially greater than the coefficient of coupling between said intermediate and outermost windings and between said outermost and innermost windings.

6. A high-frequency transformer according to claim 5 in which said three helical windings are positioned co-axially with respect to each other.
7. A high-frequency transformer according to claim 5 in which the axial length of winding of said outermost and intermediate windings is substantially greater than the axial length of said innermost winding.
- 10 8. A high-frequency transformer according to claim 5 in which the axial lengths of said outermost and intermediate windings are approximately equal and are substantially greater than the axial length of said innermost winding and said innermost winding is positioned adjacent one end of said intermediate winding.
- 20 9. A high-frequency transformer comprising a secondary and two primary windings, said secondary winding being positioned within said first primary winding and said second primary winding being positioned within said secondary winding, the spacing between said first primary winding and said 25 secondary winding being substantially greater than the spacing between said secondary winding and said second primary winding, whereby close coupling exists between said second primary winding and said 30 secondary winding and moderate coupling exists between said first primary winding and said secondary winding.
10. A high-frequency transformer according to claim 9 in which said windings are helical and the diameter of said second primary winding is nearly as great as that of said secondary winding and the diameter of said first primary winding is substantially greater than that of said secondary winding.
- 35 40 In testimony whereof I affix my signature.
HAROLD A. WHEELER.

CERTIFICATE OF CORRECTION.

Patent No. 1,846,701.

Granted February 23, 1932, to

HAROLD A. WHEELER.

It is hereby certified that error appears in the printed specification of the above numbered patent requiring correction as follows: Page 1, line 3, for the word "turnable" read tunable, and line 73, for "June 30" read June 10; page 2, line 90, for "unit-controlled" read uni-controlled; page 4, line 52, strike out the word "in"; page 5, line 36, for "arrangement" read arrangements; and that the said Letters Patent should be read with these corrections therein that the same may conform to the record of the case in the Patent Office.

Signed and sealed this 5th day of April, A. D. 1932.

(Seal)

M. J. Moore,
Acting Commissioner of Patents.
